ATTORNEY

UNITED STATES PATENT OFFICE.

ARMAND BAYARDI, OF CHICAGO, ILLINOIS.

BRACELET.

1,357,139.

Specification of Letters Patent.

Patented Oct. 26, 1920.

Application filed May 22, 1920. Serial No. 383,502.

To all whom it may concern:

Be it known that I, ARMAND BAYARDI, a citizen of the United States, residing at Chicago, in the county of Cook and State of Illinois, have invented certain new and useful Improvements in Bracelets, of which the following is a specification.

This invention relates to jewelry and more particularly to articulated ornaments such as bracelets, necklaces and the like.

The principal object of the invention is to provide a chain composed of flat links for use as a bracelet or necklace the links or sections of which are so connected as to be practically unbreakable under ordinary strains and yet may be decorated to produce an ornamental appearance.

Another object is to construct such a bracelet of blocks of metal, glass, onyx or other material flexibly connected and yet strong and durable and in which the individual blocks or sections may be easily removed and replaced when desired.

With these and other objects in view, the invention consists in certain novel features of construction as hereinafter shown and described and then specifically pointed out in the claims, and in the drawings illustrative of the preferred embodiment of the invention.

In the accompanying drawings:

Figure 1 represents a perspective view of one of the blocks or sections constituting a part of this invention.

Fig. 2 is a similar view of one of the flat doubled leaved links of the articulated connector forming a part of the invention.

Fig. 3 is a longitudinal section of a portion of a completed article.

Fig. 4 is a detail view with parts broken out.

Fig. 5 is a transverse section taken on the line 5—5 of Fig. 4, and

Fig. 6 is a side elevation of a portion of a bracelet constructed in accordance with this invention.

In the embodiment illustrated a plurality of sections 1 are connected by an articulated connector 5 shown clearly in Fig. 4. Each of these sections 1 comprises a base 2 having upstanding side walls or flanges 3 the inner faces of which are grooved longitudinally intermediate their width at 4 for a purpose presently to be described. The base of each section is shown cut out at 2^a, said cut out

portion being designed to receive gems or other suitable decorative elements (not shown).

Each of the flat double leaved links 5 is constructed as shown in Fig. 2 being composed of two substantially rectangular plates 6 and 7 formed of any suitable metal connected at one end by a neck as 8. These plates 6 and 7 have cut out portions 9, the outer end edges of which are rectilinear as 10. When the leaves or plates 6 and 7 are folded in operative position one over the other as shown in Fig. 3 the cut out portions 9 register and the neck 8 is bent to form a loop 11. This loop 11 is engaged with the straight edges of the outer end members of the plates 6 and 7 having a threaded connection therewith as is shown clearly in Fig. 3. By so uniting these links 5 it will be obvious that a very strong connection between them is effected and yet they will be sufficiently flexible for the purpose for which they are intended. When the leaves 6 and 7 of the links are arranged in lapped position the side edges thereof are 15 flush with each other and are rectilinear throughout, the width of the plates corresponding to the distance between the side walls of the grooves 4 of the sections 1. It will thus be seen that the link plates or leaves 10 may be slidably engaged with the grooves in the sections 1 as is shown clearly in Fig. 5 thereby connecting the sections 1 with each other and with the links of the chain. The chain links 5 are substantially of the same 20 length as the length of the sections 1 so that when united the joints connecting said links will be arranged at the ends of the sections providing for the flexible connection of said sections and yet permitting them to be positioned in close proximity as is shown clearly in Fig. 3 and 6.

The sections 1 when connected by the chain formed of the united links 5 may be decorated in any suitable manner and used 25 for any purpose as a bracelet, a necklace, a watch fob or for any purpose for which it may be adapted, any suitable fastener (not shown) being used for securing the end links together.

The preferred embodiment of the invention is disclosed in the drawings and set forth in the specification, but it will be understood that any modifications within the scope of the claims may be made in the 30

construction without departing from the principle of the invention or sacrificing any of its advantages.

What is claimed is:

- 5 1. An article of jewelry comprising flexibly connected sections, each section having upstanding parallel longitudinally grooved side walls, and a connector for said sections having means for slidable engagement with
10 said grooves.
2. An article of jewelry comprising a plurality of sections joined in alignment by an articulated connector, the elements of said connector corresponding substantially in
15 length to the length of the sections with their joints arranged at the ends of the sec-

tions, said sections having grooved side walls to receive the edges of said connector elements, said elements corresponding in width to the distance between the inner 20 walls of said grooves.

3. An article of jewelry composed of a plurality of flexibly connected sections, each of which comprises a base plate having upstanding side walls grooved longitudinally 25 on their inner faces, and a connector for said sections having links for entering the grooves of said sections.

In testimony whereof I affix my signature hereto:

ARMAND BAYARDI.
